UNITED STATES PATENT OFFICE.

WILLIAM ROPER, OF PHILADELPHIA, PENNSYLVANIA.

METALLIC SASH-JOINT.

1,242,242.

Specification of Letters Patent.

Patented Oct. 9, 1917.

Application filed January 9, 1917. Serial No. 141,360.

To all whom it may concern:

Be it known that I, WILLIAM ROPER, a citizen of the United States, residing at Philadelphia, in the county of Philadelphia and State of Pennsylvania, have invented 5 certain new and useful Improvements in Metallic Sash-Joints, of which the following is a specification.

My invention consists of an improved 10 sash joint. One object of my invention is to provide a strong and durable sash joint which can be used advantageously in the construction of metallic window sash of different types. My invention is also adapted 15 for floor, pavement, wall, and ceiling construction, where it is desired to retain tile, glass, and marble slabs, etc.

Another object is to so construct my improved sash joint that the muntins which 20 comprise the same can be easily and quickly joined together, and when so joined, they will be positively locked and cannot be easily distorted or moved out of their proper alignment.

25 A further object is to so construct my improved sash joint that it will be neat in appearance, of simple construction, and can be manufactured at a low cost.

These objects, and other advantageous 30 ends which will be described hereinafter, I attain in the following manner, reference being had to the accompanying drawings in which

Figure 1 is a face view showing two muntins joined together in accordance with my 35 invention.

Fig. 2 is a side elevation showing one of the muntins illustrated in Fig. 1 and drawn on a smaller scale.

40 Fig. 3 is a section on the line 3—3 of Fig. 2.

Fig. 4 is a side elevation of the muntin shown in Fig. 2 showing certain of the portions thereof bent out of their normal 45 positions.

Fig. 5 is a view of the same muntin illustrated in Figs. 2 to 4 inclusive showing the same bent in a position to receive a second muntin as will hereinafter be more 50 fully described.

Fig. 6 is a side elevation of the other of the muntins shown in Fig. 1 and drawn on a reduced scale.

55 Fig. 7 is a section on the line 7—7 of Fig. 6.

Fig. 8 is a section taken on the line 8—8 of Fig. 1.

Fig. 9 is a view of similar nature to Fig. 8 showing certain of the parts prior to the finishing operation. 60

Fig. 10 is a section on the line 10—10 of Fig. 1.

Referring to the drawings, my improved sash joint as illustrated in connection with Fig. 1, comprises two muntins 1 and 2 which are preferably made of malleable metal such as iron or steel, the muntin 1 having a head 3 which in cross section extends transversely of the elongated leg portion 4 as clearly illustrated in Figs. 2 to 70 5 inclusive.

The head 3 extends at either side of the leg 4 to provide angular recesses 5 and 6 to permit the glazing of the sash if the latter is to be used as a window or to permit the insertion of tile, marble, or other material if the latter is to be used for other purposes as above described. Both the head 3 and the leg 4 extend longitudinally throughout the length of the muntin and in carrying out my invention, the muntin 1 is punched or otherwise cut to provide an opening 7 as clearly illustrated in Fig. 2. 80

The opening 7 includes an extension 8 which is cut directly out of the leg 4, while the remaining portion 9 of said opening is cut out of the head 3. The portion 9 of said opening does not extend entirely to the outer edge surface 10 of said head but stops short thereof as clearly illustrated in Fig. 90

2. A strip of metal 11 thus remains between the opening 7 and the edge surface 10, and this portion is split or cut at 12 to form two lips, 13 and 14 respectively, directly at the crown 15 of the head 3. 95

The portion 9 of the opening 7 extends beyond both sides of the extension 8 and is of such shape, as will hereinafter be more fully described, to permit the insertion of the head 16 of the muntin 2, the latter being 100 in the present instance substantially similar to the head 3 of the muntin 1.

The lips 13 and 14 are bent outwardly as shown in Fig. 4 and the entire muntin is then bent into the position shown in Fig. 5 to receive the muntin 2, the latter in the present instance is of substantially the same cross section as the muntin 1 and includes a leg portion 17 which is located centrally 105 between the outer edges of the head 16 to pro- 110

vide recesses 18 and 19 to permit glazing as described in connection with the recesses 5 and 6 of the muntin 1.

The crown 20 of the muntin 2 is notched 5 at 21 and this notch is undercut or dove-tailed, the flare of the dove-tailed notch being in the direction of the depth of the muntin 2, as shown in Fig. 6. The leg 17 is also notched at 22 and this notch extends inwardly from the edge 23 a distance substantially equal to the width of the material 24 extending between the inner end 25 of the extension 8 of the opening 7 in muntin 1 and the adjacent edge 26 thereof. Furthermore, the notch 22 is in alignment with the dove-tailed notch 21.

The muntin 2 is inserted transversely within the opening 7 of the muntin 1, while the latter is in the position shown in Fig. 20 5, the notch 22 of the muntin 2 acting as a cavity into which fits the portion 24 of the muntin 1, thus permitting the edge 23 of the muntin 2 to be substantially flush with the edge 26 of the muntin 1 when the latter 25 is rebent into its normal position, such position being shown in Fig. 4.

It will thus be noted that the extension 8 of the opening 7 forms a cavity for receiving the portion 27 of the muntin 2, the head 16 30 of said latter muntin fitting within the remaining portion 9 of said opening 7. After the muntins have been joined as just described, the lips 13 and 14 are hammered into the dove-tailed notch 21 of the muntin 2 and when thus hammered, the material which 25 forms the lips 13 and 14 naturally is expanded and fits said dove-tailed notch 21.

Fig. 8 of the drawing shows the position 40 of one of the lips prior to being hammered into the notch 21, while Figs. 1, 9, and 10, illustrate the lips after they have been hammered into the notch 21.

It will be noted that the outermost end 45 of the dove-tailed notch 21 is of a width sufficient to receive the lips 13 and 14, and that the notch 21 is of less depth than the thickness of the lips 13 and 14, so that when the lips are hammered into the notch 21, they will spread to fill the undercut portion thereof, and the outer edge surface 10 of said lips will be flush with the outer edge surface 28 of the muntin 2.

In other words, I can so proportion the 55 amount of undercut of the notch 21 that the difference in the thickness of the lips 13 and 14 will be substantially equal to the amount of undercut of said notch 21. This is clearly illustrated in Figs. 8 and 9.

Fig. 9 shows the position of one of the 60 fingers before they are expanded, while Fig. 8 shows said finger in its expanded position.

From the above description, it will be understood that the finished joint will include muntins which neatly intersect each other, 65 and are so joined that they are positively

locked, and to disconnect the muntins, it would be necessary to cut the leg portions, since the lips are firmly embedded within the dove-tailed notch. This construction adds greatly to the strength of the joints 70 and is extremely practical for all purposes where metallic frame construction is required.

While I have described my invention as taking a particular form, it will be understood that the various parts of my invention may be changed without departing from the spirit thereof, and hence I do not limit myself to the precise construction set forth, but consider that I am at liberty to 80 make such changes and alterations as fairly come within the scope of the appended claims.

Having thus described my invention, what I claim as new and desire to secure by Letters Patent is:

1. A joint including two muntins, one muntin having a dove-tailed notch flared inwardly in the direction of the depth thereof, the other muntin being designed to straddle said first muntin and having lips designed to be forced through the narrow opening of said notch and afterward expanded therein, substantially as described. 90

2. A joint including two muntins, one muntin having notches formed in opposite edges, one of said notches being dove-tailed and flared inwardly in the direction of the depth thereof, said second muntin having an opening terminating in two lips at one edge, 100 said opening being designed to transversely receive said first muntin, the portion of said second muntin between the opening and the edge opposite said first edge being designed to enter the other of said notches in the first-mentioned muntin, said lips being designed to be forced through the narrow opening of said dove-tailed notch and afterward expanded therein, substantially as described. 105

3. A joint including two muntins, one muntin having notches formed in opposite edges, one of said notches being dove-tailed in shape and flared inwardly in the direction of the depth thereof, said second muntin having an opening terminating in two lips 110 at one edge, said opening being designed to transversely receive said first muntin, the portion of said second muntin between the opening and the edge opposite said first edge being designed to enter the other of said notches in the first-mentioned muntin, said lips being designed to be forced and expanded within said dove-tailed notch, said dove-tailed notch being of less depth than the original thickness of the lips prior to 115

their being forced and expanded therein, to permit the outer surfaces of the lips to be flush with the adjacent outer surface of the adjoining muntin, substantially as described. 125

4. A joint including two muntins each 130

having a leg portion, and a head portion extending beyond said leg portion to form recesses for glazing, the crown of the head of one of said muntins having a dove-tailed notch flared inwardly in the direction of the depth thereof, the leg portion of said latter muntin also having a notch extending inwardly from its outer edge, said other muntin having an opening in its head with an extension thereof into its leg, the portion of the opening in the head substantially corresponding in cross section with the cross section of the head of said first muntin, the crown of said second muntin being split inwardly from its outermost edge to said opening thereby providing lips, said lips being designed to be forced through the narrow opening of said dove-tailed notch and afterward expanded, the material between the extension of said opening and the adjacent edge of the leg of said second muntin being designed to fit within the notch in the leg of said first muntin, substantially as described.

5. A joint including two muntins each having a leg portion, and a head portion extending beyond said leg portion to form recesses for glazing, the crown of the head of one of said muntins having a dove-tailed notch flared inwardly in the direction of the depth thereof, said other muntin having an opening in its head with an extension thereof into its leg, the portion of the opening in the head substantially corresponding in cross section with the cross section of the head of said first muntin, the crown of said second muntin being split inwardly from its outermost edge to said opening thereby providing lips, said lips being designed to be forced through the narrow opening of said dove-

tailed notch and afterward expanded therein, substantially as described.

6. A joint including two muntins, one muntin having a dove-tailed notch flared inwardly in the direction of the depth thereof, the other muntin being designed to transversely straddle said first muntin and having a portion designed to be forced through the narrow opening of said dove-tailed notch and afterward expanded therein, substantially as described.

7. A joint including two muntins, one muntin having a notch therein flared in the direction of the depth of said muntin, the other muntin being designed to transversely straddle said first muntin and having lips designed to be forced within said notch, substantially as described.

8. A joint including two muntins, one muntin having notches formed in its opposite edges, said second muntin having an opening terminating in two lips at one edge, said opening being designed to transversely receive said first muntin, the portion of said second muntin between the opening and the edge opposite said first edge being designed to enter one of said notches in the first-mentioned muntin, said lips being designed to be forced within said other notch in the first-mentioned muntin, said latter notch being flared in the direction of the depth of the muntin in which it is formed, substantially as described.

In testimony whereof I have signed my name to this specification in the presence of two subscribing witnesses.
